(57) **CLAIM**

The ornamental design for a tire rim, as shown and described.

DESCRIPTION

FIG. 1 shows a front view of my design for a tire rim; FIG. 2 shows a perspective view of the tire rim shown in FIG. 1;

FIG. 3 shows a front view of a second embodiment of my invention;

FIG. 4 shows a perspective view of the tire rim shown in FIG. 3;

FIG. 5 shows a front view of a third embodiment of my invention; and,

FIG. 6 shows a perspective view of the tire rim shown in FIG. 5.

The broken line showing of environment is for illustrative purposes only and forms no part of the claimed design.
